G. A. LYON

VEHICLE BUFFER CONSTRUCTION

Filed May 9, 1923

George Albert Lyons
By his Attorney
Harry H. MacLean

UNITED STATES PATENT OFFICE.

GEORGE ALBERT LYON, OF PHILADELPHIA, PENNSYLVANIA.

VEHICLE BUFFER CONSTRUCTION.

Application filed May 9, 1923. Serial No. 637,671.

To all whom it may concern:

Be it known that I, GEORGE ALBERT LYON, a citizen of the United States, and resident of Philadelphia, county of Philadelphia, 5 State of Pennsylvania, have made a certain new and useful Invention Relating to Vehicle Buffer Constructions, of which the following is a specification, taken in connection with the accompanying drawing, which 10 forms part of the same.

This application is a partial continuation of my copending application, Serial No. 632,076, filed April 14, 1923, and contains subject matter taken therefrom.

15 In the accompanying drawing showing a somewhat diagrammatic way various illustrative embodiments of this invention:

Fig. 1 is a front view of an illustrative buffer.

20 Fig. 2 is a bottom view thereof.

Fig. 3 shows an edge bent strip of blank, and

Figs. 4 and 5 show a buffer element which may be formed therefrom.

25 Fig. 6 shows another edge bent strip or blank, and

Figs. 7 and 8 show a buffer element which may be formed therefrom, and

30 Fig. 9 is a front view of a buffer which may be formed of such elements.

In the illustrative buffer shown in Figs. 1 and 2 the buffer front may be formed of two adjustably connected front elements of relatively wide thin spring steel strip. One 35 of these elements may comprise the vertically or transversely separated front strips, 1 and 5, connected at the buffer end by an edge bent coned up integral connector portion 26 which may, as indicated in Fig. 2, be

40 rearwardly inclined adjacent the automobile wheels. The portions of these buffer front strips forming this element 3 may, as indicated in Fig. 1, be converging adjacent the coned up connector portion so as to come

45 together considerably at about the point 23 so that the distance of these strip edges may be reduced to 1 or 2 inches, if desired. It is also desirable in most cases to have the inner portions of the element from about

50 the strip 4 to the strip ends 2, 6 substantially parallel and the strips may be closely spaced in this vertically or transversely separated position so that their edges 37 may be an inch and a half or so apart be-

55 tween the clamping devices such as 12 which many adjustably clamp the elements

together. The other cooperating element 9 may have similar vertically displaced or transversely separated front strips 7 and 10 which may be parallel between the strip ends 8 and 11, and the ends 2, 6 of the other element. These strips may be joined by an integral connector portion 26 of similar configuration and similarly rearwardly inclined as shown in Fig. 2. Where the coned up edge bent connector portion is arranged in about this way the adjacent portions of the strip members may be oppositely inclined at angles of 10 to 20° more or less from the vertical and then the inwardly extending 60 portions of these strips may be oppositely twisted to bring the strips into substantial vertical alignment by the time the clamping devices or the other overlapping strip ends are reached. The clamping devices may 65 not only securely clamp or connect the overlapping strips in laterally adjusted position but may also securely connect to each of these strips in both the upper and lower vertically separated members of the buffer 70 front, the wide connecting portions of the supporting or attaching members such as the inturned connecting portions 14, 20 shown in Fig. 2, which may be clamped to the buffer front members by the clamping 75 bolts 13. These attaching members may 80 also be formed of hardened and tempered spring steel strip, if desired, and may have the curved resilient portions 15, 16, 18, 19 which are adapted to be connected to the 85 automobile in any suitable way as by the laterally extending brace bar portion 17 which may be clamped securely to the frame ends 21.

Buffer elements of this type may be conveniently made by forming an edge bent connector portion 26 in the buffer strip as shown in Fig. 3. This may be done by bending the strip around suitable forms when properly heated and it is sometimes desirable to bend or curve it toward each other the adjacent portions of the strip near this edge bent connector portion so that the inner edges of the strip curve in somewhat at about the points 23, the outer portions or 90 strip ends 1, 5 being preferably straight and diverging at a considerable angle from this integral connector portion. In this way an edge bent buffer strip or blank 27 is formed which may advantageously be coned or 100 shaped up by cold or hot bending processes, in some cases at the same heat as when the

original edge bend is formed therein. This coning up of the edge bent connector portion 26 to some such position as is indicated in Figs. 4 and 5 naturally contracts this bent 5 connector portion and brings the connected strip ends 1 and 5 correspondingly closer together, the adjacent portions of these strip members converging at about the points 23 as is indicated in Fig. 4. In this way the 10 original diameter or radius of the edge bent blank shown in Fig. 3 may be considerably reduced and the space between the adjacent edges 36 of this element may, if desired, be only a quarter or a sixth of the inner diameter 15 of the coned up connector portion 26 which may, if desired, be rearwardly inclined to some such extent as is indicated in Fig. 2. Thus as seen in Figs. 4 and 5, the larger outer edge 25 of this connector portion 26 20 is located behind or to the rear of its smaller inner edge 24 and of course the strips may be oppositely twisted from about the point 23 where they are oppositely inclined, so that their inner portions at about the point 1, 5 25 in Fig. 4 may be in substantial transverse alignment, if desired.

Another form of blank suitable for this purpose is shown in Fig. 6 as comprising the edge bent connector portion 31 joining the 30 integral diverging strips or members 32, 34 of such wide thin buffer stock which may be flat spring steel, if desired. After edgewise bending such a blank as 28 the edgewise, bent portion may be coned or formed up so 35 as to be considerably contracted as is indicated in Figs. 7 and 8, where this action reduces the divergence between the strip ends 32, 34, which may be brought together into parallel or somewhat converging form, if 40 desired. This generally conical configuration or forward projection or bending of the inner edge 29 of the edge bent blank may, as indicated in Figs. 6 and 7, reduce the curvature or diameter or transverse width of this 45 inner edge of the blank to about half or so its original value, and the adjacent connected strips may thus be brought together so that their edges 35 may be only 2 or 3 inches or so apart, which gives a very desirable ar- 50 rangement for automobile buffer elements. Of course, if desired, the oppositely inclined portions of the strip members adjacent the connector portion may be bent or oppositely twisted so as to flatten them into the same 55 vertical or transverse plane if this is desired. This coning up or somewhat conical forward bending of the edge bent blank or buffer makes it possible to limit the edge bending of the blank to an amount which does not 60 undesirably strain or distort it and then bring the diverging ends of such blanks as is shown in Fig. 3 or Fig. 6 into such contracted position at the bend that the connected strips are brought together into 65 closely spaced parallel or other relation, as

desired, for the buffer element. All these bending operations may of course be performed while the buffer strips are partly or entirely heated and the finally shaped elements may be heat treated as by being oil quenched and tempered where this is desired for additional resilient strength. The buffer front or other elements may also be suitably finished as by having more or less of their surfaces ground, polished and nickel plated or japanned or otherwise finished. Fig. 9 shows an illustrative buffer which may be formed from such elements as are illustrated in Figs. 7 and 8. Two such elements are there shown as adjustably secured with their strip ends 2, 6 and 8, 11 in overlapping position adjacent the clamping members 12, which may also connect these buffer front elements to the supporting attaching devices of the type shown and described in connection with Figs. 1 and 2.

This invention has been described in connection with a number of embodiments, forms, proportions, sizes, parts, arrangements, materials, methods of construction, connection and use, to the details of which disclosure the invention is not of course to be limited, since what is claimed as new and what is desired to be secured by Letters Patent is set forth in the appended claims.

I claim:—

1. The automobile buffer comprising two adjustably connected elements formed of wide thin steel strip and each comprising vertically spaced horizontally extending portions and comprising at the end of the element an integral connector portion of the strip edge bent and coned up and thereby contracted to bring the horizontally extending vertically spaced end portions of the strips into closely spaced substantially vertical alignment with their adjacent edges about two to five inches apart, and an attaching member adapted to be secured to the automobile frame and having laterally extending connecting portions rigidly secured to both vertically separated portions of each of said elements adjacent the ends of said buffer front.

2. The automobile buffer comprising two connected elements formed of wide thin steel strip and each comprising vertically spaced horizontally extending portions and comprising at the end of the element an integral connector portion of the strip edge bent and coned up and thereby contracted to bring the horizontally extending vertically spaced end portions of the strips into closely spaced substantial vertical alignment, and an attaching member adapted to be secured to the automobile frame and having laterally extending connecting portions rigidly secured to both vertically separated portions of each of said elements.

3. The automobile buffer comprising two

- connected elements formed of wide thin steel strip and each comprising vertically spaced portions and comprising at the end of the element an integral connector portion of the strip edge bent and coned up and contracted to bring the vertically spaced end portions of the strips into closely spaced position, and an attaching member adapted to be secured to the automobile frame and having connecting portions rigidly secured to both vertically separated portions of each of said elements. 5
4. The automobile buffer comprising two connected elements formed of wide thin steel strip and each comprising vertically displaced portions and comprising at the end of the element an integral connector portion of the strip edge bent and contracted to bring the vertically displaced end portions 10 of the strips into closely spaced position, and an attaching member adapted to be secured to the automobile frame and having connecting portions secured to said elements. 20
5. The automobile buffer comprising connected elements formed of wide thin steel strip and each comprising vertically spaced horizontally extending portions and an integral connector portion edge bent and bent into projecting substantially conical form 25 to bring the adjacent portions into closely spaced vertically spaced position and arranged in oppositely inclined angular position, said vertically spaced portions being oppositely twisted adjacent said connector portion to bring the strip ends into substantial vertical alignment, and an attaching member adapted to be secured to the automobile frame and secured to both said elements. 35
6. The automobile buffer comprising connected elements formed of wide thin steel strip and each comprising vertically spaced portions and an integral connector portion edge bent and bent into projecting substantially conical form to bring the adjacent portions into closely spaced vertically spaced position and an attaching member adapted to be secured to the automobile frame and secured to both said elements. 40
7. The automobile buffer front comprising connected elements formed of wide thin tempered spring steel strip and each comprising vertically spaced horizontally extending portions and comprising at the end 45 of the element a rearwardly inclined integral connector portion of the strip edge bent and coned up to hold the adjacent transversely spaced portions in converging oppositely inclined position, said adjacent transversely spaced portions being oppositely twisted to bring the connected strip ends into substantial vertical transverse alignment near the center of the buffer front with their adjacent edges about two to 50 inches apart. 65
8. The automobile buffer front comprising connected elements formed of wide thin steel strip and each comprising vertically spaced portions and comprising at the end of the element a rearwardly inclined integral connector portion of the strip edge bent and coned up to hold the adjacent transversely spaced portions in converging closely spaced position. 70
9. The automobile buffer front comprising connected elements formed of wide thin spring steel strip and each comprising transversely spaced horizontally extending strip end portions and comprising at the end of the element an integral connector portion of the strip edge bent and coned up to hold the adjacent transversely spaced portions in closely spaced oppositely inclined positions, said adjacent transversely spaced portions being oppositely twisted to bring the connected strip ends into substantial transverse alignment with their adjacent edges about two to four inches apart. 75
10. The automobile buffer front comprising connected elements formed of wide thin spring steel strip and each comprising transversely spaced horizontally extending strip end portions and comprising at the end of the element an integral connector portion of the strip edge bent and coned up to hold the adjacent transversely spaced portions in closely spaced inclined positions, said adjacent transversely spaced portions being twisted to bring the connected strip ends into substantial transverse alignment. 80
11. The automobile buffer front comprising connected elements formed of wide thin steel strip and each comprising transversely spaced horizontally extending portions and comprising at the end of the element a rearwardly displaced integral connector portion of the strip edge bent and coned up to hold the adjacent transversely spaced portions in closely spaced converging positions with their adjacent edges about two to four inches apart. 85
12. The automobile buffer front comprising connected elements formed of wide thin steel strip and each comprising transversely spaced horizontally extending portions and comprising at the end of the element an integral connector portion of the strip edge bent and coned up to hold the adjacent transversely spaced portions in closely spaced position. 90
13. The automobile buffer front element formed of wide spring steel strip and comprising transversely spaced portions and comprising at the end of the element a rearwardly inclined integral connector portion of the strip edge bent and coned up with its outer edge further rearward than its inner edge to contract said connector portion and hold the adjacent transversely 125
- 130

spaced portions in converging closely spaced position.

14. The automobile buffer element formed of wide steel strip and comprising transversely spaced portions and comprising at the end of the element a rearwardly inclined integral connector portion of the strip edge bent and coned up with its outer edge further rearward than its inner edge to contract said connector portion and hold the adjacent transversely spaced portions in more closely spaced position.

15. The automobile buffer front element formed of wide thin tempered spring steel strip and comprising transversely spaced portions and comprising at the end of the element a rearwardly inclined integral connector portion of the strip edge bent and coned up to contract said connector portion and hold the adjacent transversely spaced portions in converging oppositely inclined positions, said adjacent transversely spaced portions being oppositely twisted to bring the connected strip ends into substantial transverse alignment with their adjacent edges about two to four inches apart.

16. The automobile buffer front element formed of wide thin steel strip and comprising transversely spaced portions and comprising at the end of the element a rearwardly inclined integral connector portion of the strip edge bent and coned up to contract said connector portion and hold the adjacent transversely spaced portions in oppositely inclined positions.

17. The automobile buffer element formed of wide thin steel strip and comprising transversely spaced portions and comprising at the end of the element an integral connector portion of the strip edge bent and somewhat coned up to contract said connector portion and hold the adjacent transversely spaced portions in converging oppositely inclined positions with their adjacent edges at the strip ends about two to four inches apart.

18. The automobile buffer element formed

of wide thin steel strip and comprising transversely spaced portions and comprising at the end of the element an integral connector portion of the strip edge bent and somewhat coned up to contract said connector portion and hold the adjacent transversely spaced portions in oppositely inclined positions.

19. The automobile buffer front element formed of wide thin steel strip and comprising transversely spaced portions and comprising at the end of the element a rearwardly inclined integral connector portion of the strip edge bent and substantially coned up to contract said connector portion and hold the adjacent transversely spaced portions in converging closely spaced positions.

20. The automobile buffer front element formed of wide thin steel strip and comprising transversely spaced portions and comprising at the end of the element an integral connector portion of the strip edge bent and substantially coned up to contract said connector portion and hold the adjacent transversely spaced portions in closely spaced positions.

21. The automobile buffer front element formed of steel strip and comprising transversely spaced portions and comprising at one end of the element an integral connector portion of the strip edge bent and coned up to contract said connector portion and hold the adjacent transversely spaced portions in closely spaced positions with adjacent edge portions about two to four inches apart.

22. The automobile buffer front element formed of steel strip and comprising transversely spaced portions and comprising at one end of the element an integral connector portion of the strip edge bent and coned up to contract said connector portion and bring together the adjacent transversely spaced portions.

GEORGE ALBERT LYON.
